MULTICOLOR PRINTING MACHINE

Adolph M. Zuckerman, New York, N. Y., assignor
to R. Hoe & Co., Inc., New York, N. Y., a cor-
poration of New York

Application June 30, 1943, Serial No. 492,924

3 Claims. (Cl. 270—20)

This invention relates to printing machines, and more particularly to rotary perfecting multi-color printing machines in which accurate impression register is required.

In modern high speed rotary perfecting multi-color presses for producing high grade printing in which accurate printing register is required, such as magazine work, it is desirable that the printing and other units of the machine be so constructed, arranged and located with respect to each other as to produce the best results while occupying a minimum of space. To produce the required results, the web should be dried between each printing impression and the freshly printed side or surface of the web should not be engaged by any component of the machine until the web is passed through a drying device to thereby prevent "smutting" of the web. The quality of the printing may be further improved by drying the web by heating and cooling the web after each impression, and arranging the components of the machine so that the freshly printed surface of the web is not engaged by a roller or other component of the machine until the web has been heated and cooled, or at least partially cooled.

It is well known in the printing art that smutting, due to the freshly printed ink engaging a roller, turner bar or other component of the machine, is one of the obstacles that has obviated the attainment of greater printing speeds in magazine presses, and it is only in recent years that steps have been taken to overcome this. The web leads or arrangements disclosed in recent patents accomplish this result, but so far as applicant knows, no multi-unit arrangement, such as that disclosed herein, has been heretofore provided to heat and cool the web after each impression before its freshly printed surface engages a component of the machine, to provide positive web control, relatively short web leads between successive printing impressions, and to also afford convenient access to the operable and manipulative components of the machine.

It is, therefore, an object of this invention to provide a multi-unit rotary multi-color perfecting printing machine in which the freshly printed web is dried by heating and cooling it immediately following the printing of each impression without the freshly printed surface of the web engaging any instrumentality of the printing machine until the ink is sufficiently dried.

An additional object of this invention is to provide a multi-unit rotary multi-color perfecting printing machine in which the freshly printed web is dried by heating and cooling it between

successive printing impressions prior to its freshly printed surface engaging any instrumentality of the machine, and in which the units are so constructed, arranged and located as to insure positive web control and convenient accessibility to the units of the printing machine.

Another object of this invention is to provide a multi-unit rotary multi-color perfecting printing machine in which the web is dried by heating and cooling it immediately following the printing of each impression, and in which the printing units and machine components are so constructed and arranged and also so located with respect to each other as to form a web loop of substantially closed formation.

A further object of this invention is to provide a multi-unit rotary multi-color perfecting printing machine in which the web is dried by heating and cooling it immediately following the printing of each impression, and in which the printing units and guide components are so constructed and arranged and also so located with respect to each other that they form a web loop, and components of the machine being located within the loop.

A more specific object of this invention is to provide a multi-unit rotary multi-color perfecting printing machine in which the web is dried by heating and cooling it immediately following the printing of each impression, and in which the printing units and guide components are so constructed and arranged and also so located with respect to each other as to produce web loops of substantially closed formation with the certain component of the machine being located within each loop, and the impression cylinders of each printing unit being located within the loop and positioned with their axes in parallelism.

It is also an object of this invention to provide a multi-unit rotary perfecting multi-color printing machine of generally improved construction, whereby the device will be simple, durable and inexpensive in construction, as well as convenient, practical, serviceable and efficient in its use.

With the foregoing and other objects in view, which will appear as the description proceeds, the invention resides in the combination and arrangement of parts and in the details of construction hereinafter described and claimed, it being understood that various changes in form, proportion, and minor details of construction may be made within the scope of the claims without departing from the spirit or sacrificing any advantages of the invention.

For a complete disclosure of the invention, a detail description of it will now be given in connection with the accompanying drawings, which form a part of the specification, wherein—

Figure 1 is a diagrammatic side elevation depicting the improved multi-unit rotary web perfecting multi-color printing machine.

Figure 2 is a fragmental diagrammatic plan view of the reversing turner bars, the view being seen in the direction of arrow 2 of Figure 1.

Figure 3 is a fragmentary diagrammatic side elevation depicting a modified arrangement of the invention.

Figure 4 is a diagrammatic end view thereof, the view being seen in the direction of arrow 4 of Figure 3, and

Figure 5 is an enlarged diagrammatic side elevation depicting the first group of printing units.

Referring to the drawings, in which similar reference characters designate corresponding parts, 10 indicates the supporting frame for the various components and printing units of the printing machine, and portions of this frame have been omitted to better illustrate the invention. Conventional web supply or feed rolls 11 are rotatably supported from the machine, in conformity with the usual practice, and a web W is led from a roller 11 through a tension control device 12 of conventional construction, and through feed rollers 13 of any preferred construction and under guide rollers 15 to the first printing unit 16 of the machine.

Each printing unit of the machine includes an impression cylinder 17 and a cooperating plate or form cylinder 18 to which ink is supplied from an inking mechanism. The inking mechanism may be of any preferred construction, and, in the present instance, there is depicted a fountain roller 20, ductor roller 21, ink cylinders 22, ink distributing rollers 23, transfer rollers 25, and form rollers 26. It is to be understood, of course, that the inking mechanism here depicted is typical of a number of preferred constructions that may be employed within the scope of this invention, but the disclosed arrangement has been found highly satisfactory in magazine printing.

The web W is led from the first printing unit 16, around a guide roller 21, through a heating unit 28, around a guide roller 29, and then around a pair of suitable cooling rollers 30. The heating unit is preferably of the gas fuel type in which the temperature adjacent the web is raised sufficiently to vaporize the ink solvent and this vapor is ignited by the gas flame from gas burners of the type disclosed in U. S. Patents Nos. 2,042,432 and 2,129,277. Although the employment of this type of heating unit is preferred, any conventional heating unit which raises the temperature of the web sufficiently to dry the freshly printed web will suffice for the purpose of this invention.

From the cooling rollers 30 the web is led around guide roller 31 to another printing unit 16a, similar to the unit 16, where a second impression is printed on the same or obverse side of the web. After the web passes between the impression cylinder 17 and form cylinder 18 of the unit 16a, it is led around a guide roller 33 and through another heating unit 28a. After the web passes through the heating unit 28a it is guided around a guide roller 35 to and around another pair of cooling rollers 30a, and then around guide rollers 36 and between the impression and form cylinders 17 and 18 of a third printing unit 16b. From this point the web is led around a guide

roller 38 through a third heating unit 28b, and then around a guide roller 40 to and around a third pair of cooling rollers 30b. After passing around the cooling rollers 30b, the web is led

5 around a guide roller 41 and between the impression and form cylinders 17 and 18 of a fourth printing unit 16c. From this point the web is led under guide rollers 43, through a fourth heating unit 28c, and then around a guide roller 45 to 10 and around a fourth pair of cooling rollers 30c. After the web passes the cooling rollers 30c, it is led around a guide roller 46, and then over a conventional turner bar 47, as best indicated in Figure 2, around a guide roller 48, over another conventional turner bar 50 to thereby reverse 15 the web in conformity with the usual practice.

With this arrangement, the web is led through the four printing units and the four heaters, and around the guide rollers and cooling rollers to 20 form a web loop, and the heating unit 28c, cooling rollers 30c, and the web reversing components are all located within the web loop. Figure 1 of the drawings shows the first and second printing units 16 and 16a respectively, mounted with unit 16a in superposed relation to unit 16 and with their impression cylinders 17 located adjacent a vertical plane. The third and fourth printing units 16b and 16c are likewise mounted with unit 16c in superposed relation to unit 16b and with their impression cylinders located adjacent a second vertical plane.

The reversed web is then led from the turner bar 50 around and past guide rollers 51 and in aligned relation to the web of the loop, to a printing unit 16d, similar to the unit 16. This unit forms the first of a group of units for printing on the reverse side of the web to thereby perfect it. After the web passes between the impression and form cylinders 17 and 18 of the first perfecting unit 16d, it is led by guide rollers, similar to those hereinbefore disclosed, through a heating unit 28d, around cooling rollers 30d, between the impression and form cylinders 17 and 18 of a second perfecting unit 16e, through a heating unit 28e, around cooling rollers 30e, between the impression and form cylinders 17 and 18 of a third perfecting unit 16f, through a heating unit 28f, around cooling rollers 30f, between the impression and form cylinders 17 and 18 of a fourth perfecting unit 16g, through a heating unit 28g, and around cooling rollers 30g.

After the web is cooled by the rollers 30g, it is led around and past guide rollers 52, to a web-propelling roller 53 which may be engaged by a slit disk 55 to thereby slit the web into a number of ribbons, and then the web or ribbons are led to a conventional magazine folder 56, which is located in line with the printing units, where the webs are folded into the desired product in conformity with the usual practice which is well understood by those skilled in the art, consequently the folder is merely indicated in diagrammatic form in this application.

By this arrangement, the web is first led from 65 the supply roll 11, through four printing units and four heaters, and around four sets of cooling rollers, in such manner that the web is led clockwise in the same sense through the printing units and heaters to form a first loop. The printing units 16, 16a, 16b and 16c, through which the web W is led to form the first loop, print on the first or obverse side of the web, and the units 16d, 16e, 16f and 16g, through which the web is run to form the second loop, print on the reverse 70 side of the web to thereby perfect the web in

multi-color. The final heating unit 28c of the first web loop is located within the loop, together with the cooling rollers 30c and the disclosed conventional web reversing mechanism, and the final heating unit 28g of the second web loop is located within the loop, together with its cooling rollers 30g.

The printing units and wet drying components are located in such relation to each other that immediately the web receives each printing impression it is heated and cooled and then run directly to the next printing unit, which arrangement insures relatively short web leads between adjacent printing units for printing on the same side of the web, thereby insuring accurate registration of the superimposed impressions.

In Figures 3 and 4, a slightly modified form of my invention is disclosed in which the folder 56a is located directly opposite, or to one side of, the final heating unit 28g, as best seen in Figure 4. In this arrangement, after the web has passed around the final cooling rollers 30g, it is led around a guide roller 46a and over a turner bar 47a. From the turner bar 47a the web is led around guide rollers 57 to the folder 56a, which is similar to folder 56, where the product is formed, as hereinbefore disclosed.

This modified arrangement of the invention is advantageously employed in printing plants where there is not sufficient longitudinal floor space to accommodate the first disclosed form of the invention.

It will be understood that the invention may be embodied in other specific forms without departing from the spirit or essential attributes thereof, and it is therefore desired that the present embodiment be considered in all respects as illustrative and not restrictive, and it will be further understood that each and every novel feature and combination present in or possessed by the mechanism herein disclosed forms a part of the invention included in this application.

What is claimed as new and useful is:

1. In a multi-color web printing machine, a plurality of printing units, web-guide rollers and web-cooling rollers constructed and arranged to guide and support a web in loop formation and to print a plurality of impressions on one side of the web, each printing unit including a form cylinder and an impression cylinder, a cooling roller being operably located between the first and second units of each pair of operably adjacent printing units, and a heating chamber operably located between the first unit and the cooling roller of each pair of operably adjacent units, whereby the web of the loop in running from the first unit to the second unit of each pair of operably adjacent

printing units passes through a heating chamber and around a cooling roller before the printed surface of the web engages a guide roller, an additional printing unit outside the loop, means to reverse the web entirely within the loop, and means to guide the reversed web from within the loop to the said additional unit.

2. In a multi-color web printing machine, first and second printing groups, each printing group including a plurality of printing units, web-guide rollers and web-cooling rollers constructed and arranged to guide and support a web in loop formation and to print a plurality of impressions on one side of the web, each printing unit including a form cylinder and an impression cylinder, a cooling roller being operably located between the first and second units of each pair of operably adjacent printing units, a heating chamber operably located between the first unit and the cooling roller of each pair of operably adjacent units, whereby the web of the loop in running from the first unit to the second unit of each pair of operably adjacent printing units passes through a heating chamber and around a cooling roller before the printed surface of the web engages a guide roller, means to reverse the web entirely within the first loop, and guide rollers to guide the reversed web from within the first loop to the second loop whereby a plurality of impressions are printed on the reverse side of the web.

3. In a multi-color web printing machine, first and second printing groups, each printing group including a plurality of printing units, web-guide rollers and web-cooling rollers constructed and arranged to guide and support a web in loop formation and to print a plurality of impressions on one side of the web, each printing unit including a form cylinder and an impression cylinder, a cooling roller being operably located between the first and second units of each pair of operably adjacent printing units, a heating chamber operably located between the first unit and the cooling roller of each pair of operably adjacent units, whereby the web of the loop in running from the first unit to the second unit of each pair of operably adjacent printing units passes through a heating chamber and around a cooling roller before the printed surface of the web engages a guide roller, means to reverse the web entirely within the first loop, guide rollers to guide the reversed web from within the first loop to the second loop whereby a plurality of impressions are printed on the reverse side of the web, and means to guide the web from the second loop to a location outside the loop.

ADOLPH M. ZUCKERMAN.
